UNITED STATES PATENT OFFICE.

JOHANNES RUDOLF PAUL IRMISCHER, OF SAALFELD-ON-THE-SAALE, GERMANY.

SHUTTLE.

Application filed March 19, 1924, Serial No. 700,319, and in Germany March 24, 1923.

This invention refers to shuttles, and in particular to shuttles adapted for use in power looms for the weaving of wire fabrics, and it is one of the important objects of my invention to provide means whereby the capacity of the spindle is increased, so that it becomes adapted for the reception of a considerably larger amount of wire and the like than it has been possible to accomplish with shuttles of this kind heretofore in use, as far as I am aware, and it is a further object of the invention to prevent the serious drawback and inconvenience of the snapping off and slipping of the wire windings from the spindle, and in further pursuance of these and other objects means are also provided for the stretching, straightening and smoothening of the length of wire passing from the spindle. Other important objects and advantages of the invention will appear from an inspection of the drawings, and as the specification proceeds.

In view of the fact that the frequency of the exchanging of the spindles in the shuttle is in the inverse ratio of its wire containing capacity, it is obvious that any increase in capacity results in an increase in the output of the loom when operating with strong wires the suggestions in regard to the increase of the wire containing capacity of the shuttle in accordance with the previous art have mainly been based upon the providing of means for producing as large a shed as possible, and on the provision of the greatest possible shuttles with correspondingly large spools.

My invention in contradistinction to the previous art provides for the increase of wire containing capacity of the shuttle by arranging for the mounting of the spindle fastening and retaining means in the pointed end of the shuttle which heretofore was only utilized for the purpose of determining the shape of the shuttle, while the space between the two shuttle caster wheels heretofore used for the shuttle fastening means is used for the lengthening of the spindle in accordance with my invention. By thus arranging the spindle securing means in the shuttle the spool becomes, detachably, and yet firmly suspended at one of its ends, and inasmuch as with such, so to speak, floating supporting means of the spindle the otherwise necessary mounting of a separate support for the free end of the spindle is dispensed with, the new arrangement re-

sults in an increase of the wire containing capacity. In view of the objects referred to and for insuring providing a further support for the head of the spindle and substantially preventing disengagement by slipping in the axial direction, the foot of the spindle in the practise of my invention may be constructed, so as to constitute a two-sectioned protecting roof for a shuttle caster wheel, such roof being adapted to prevent dirt and foreign bodies from getting upon the caster wheel and interfering with its unimpeded rotation. The increased capacity for the reception of wire of the spindle is further assisted by providing a spindle of ellipsoidal or blade-shaped or semi-circular cross section, and in accordance therewith I may construct the shuttle itself in such a manner that in cross section its width exceeds the height of the shuttle. By the increase of the usual width of the shuttle, without necessarily increasing its height, the wire containing capacity is much augmented without requiring any increase of the opening of the shed.

Aside from the advantage of increasing the wire containing capacity of the spindle the provision of an ellipsoidal or blade-shaped or semi-circular cross section of the spindle results in the further advantage that the uncontrollable annoying slipping off of the wire windings from the spindle frequently occurring in the previous constructions of spindles, particularly with the usual bolt shaped spindles, is prevented, inasmuch as the sections of the arcs of the windings corresponding to the great axis of the ellipse set up some friction against the small arcs of the ellipsoidal cross section of the spindle, which results in retaining the arcs in position, so as to produce uniform playing out of the filling wire. This uniformity of feed of weft is further assisted and increased by disposing a suitable number of stretching, straightening and smoothening rollers, so as to be adjustably and exchangeably mounted in the shuttle, the action of these rollers being facilitated and further assisted by suitable wire discharging means comprising the combination of a frame displaceably and adjustably mounted in the wall of the shuttle with rollers disposed in an extension of the shuttle.

With these and other objects in view and in further pursuance of my invention means are provided for the purpose of securing the

different members of the shuttle in a novel manner against the effects of loosening and relaxing of parts and of the wire resulting from vibration, shaking, jolting and other causes. Other important objects and advantages will be pointed out in the specification, and will appear therefrom and from the drawings.

The invention will be more fully described 10 with reference to the accompanying drawings, showing by way of example some kind of embodiment of the main principles of my invention.

In the drawings:—Figure 1 is an elevational view of the shuttle; Figure 2 shows a 15 form of shuttle according to my invention operating without filling wire stretching means in plan view. Figures 3 and 4 are respectively side view and plan view of a 20 shuttle provided with the filling wire stretching means. Figures 5 and 6 illustrate on an enlarged scale and in fractional views with parts in section the main parts 25 of the shuttle according to Figures 1 and 2. In Figures 7 to 12 I have shown detail views 30 of parts of the spindle, Figures 7 and 8 showing the spindle in elevation and side view, respectively. Figure 9 is a section on the line A—B of Figure 8. In Figures 10 and 35 11 I have shown in a conventional diagrammatic manner the head of the spindle with a number of wire windings in elevation and in sectional view respectively. Figure 12 illustrates a modification, showing a semi-circular 40 spindle with a number of wire windings. Figures 13 and 14 are respectively side view and top plan view of the stretching, straightening and smoothening means 45 employed in my invention. Figure 15 is a section on the line c—d of Figure 14. Figures 16, 17 and 18 illustrate respectively in plan view, elevation and in sectional view the means for producing uniformity of the playing out of the filling wire.

45 The shuttle comprises a spindle 1 the foot or end portion 1^a of which may constitute a, for instance, gable shaped protecting roof for one of the caster wheels 13 of the shuttle. The caster wheel 13 is thereby protected 50 against contamination and contact with foreign bodies which are liable to drop upon the shuttle and will interfere with its smooth movement. The protecting cover or roof may be extended by a horizontal plate 55 24 (Figure 5) secured to the roof top for more securely keeping foreign bodies away from the wheel. For the protection of the other caster wheel 13^a against foreign bodies the shuttle may be provided with a plate 60 24^a (Figure 1). The foot or end portion 1^a of the spindle of substantially roof shaped configuration possesses the two hook shaped or gable shaped ends 1^b, 1^c of which the extremity 1^b is provided with a claw shaped 65 projection 4 which with the cross pin 2 of

the shuttle constitutes an open joint. The claw shaped projection 4 is of such height that the spindle 1 on being swung into the dash-and-dot position of Figure 5 is adapted to be supported upon the plane supporting 70 surface 1^d of the projection 4 without becoming disengaged from the open joint connection, so that the spindle may be automatically retained in the vertical position, whereby its manipulation is facilitated. 75 Upon the change of position of the spindle from the vertical into the horizontal position thereof the sliding faces 1^e which branch off laterally from the foot or spindle extremity 1^a slide along a cam surface 1^f of a 80 web portion 1^g of the shuttle, the foot with its projection 4 being simultaneously firmly pressed against the cross pin 2 of the shuttle, so that the spindle is secured in position. The portion 1^g is provided with the lateral 85 funnel shaped socket 5 (Figure 6) which in combination with the spring actuated pin 3, 6 of the shuttle constitutes the locking means for the spindle 1. The spring operated pin 3, 6 which is forced by its spring 6 against the funnel shaped depression 5 of the spindle end 1^a is supported on the closing plate 7 of the shuttle, which is retained by the screws 25. Against this plate 7 there abuts the rectangularly shaped leg 12^a of the 90 caster wheel axle 12 with its bevelled off face 14, the portion 12^a being thereby partially covered by the plate 7, so that the caster wheel axle is thereby securely locked in position. The said portion 12^a is preferably housed in the wall 20 of the shuttle. 95

100 The spindle 1 may be given the somewhat lenticular cross sectional shape, shown by way of example in Figures 9, 11 and 12, by which means the spindle, instead of assuming the shape of a so-called "bolt-spindle" becomes a kind of "sword-spindle" with one of its axes considerably larger than the other. The elastic wire wound upon such "sword-spindles" practically assumes the 105 sectional shape of the spool inasmuch as its windings 22 become ellipsoidal, while in the case of bolt-spindles circular windings are produced. Circular windings are spread by the spring action of the wire upon the un-tensioning of the same, so that the windings become larger than the diameter of the bolt and therefore are easily snapped off from the bolt-spindle. The windings 22 (Figs. 9, 11, 12) of the sword spindle, however, are 110 prevented from snapping off the spool, because the force of the spreading wire which tends to cause unwinding is counteracted by the friction which is set up upon the sliding of the arc shaped piece of wire 22^a corresponding to the great axis of the ellipse over the small arcs 22^b of the cross section of the sword-spindle (Figures 11 and 12). The same action takes place in the 115 case of spindles with semi-circular cross sec- 120 125 130

tion and with all those cross sections the extension of which in one direction is considerably larger than its size in other directions.

5 In accordance with the form of construction shown in Figures 1, 2, 5 and 6 there is arranged in the direction of the longitudinal axis of the spindle 1 and in front of its pointed end 8 the wire guiding eye 9 secured to the shuttle with roller 9^a over which the wire passes to the guide rollers 11 mounted in the inserted member 10 of the side wall 20 of the shuttle, before it leaves the shuttle.

10 15 In the modification of construction according to Figures 3 and 4 and Figures 13 to 18 the wire on being unwound in the longitudinal direction of the shuttle passes through the eye 25^a of the web portion 26 of the shuttle and over three or more rollers. Of these rollers 27, 28, 29 of which only three have been shown by way of example the central roller 28 possesses spring acting bearings 34, 35 adapted for adjustment by 20 means of screws 32, 33, and by means of which the tension of the filling wire may be varied with accompanying rising or lowering of the roller 28. The rollers 27, 28, 29 are mounted in a common frame 30, so as 25 to admit of being exchanged all at a time against rollers of other diameters or other arrangement, thereby facilitating the weaving of wires of any desired diameter and conditions. After the guiding of the wire 30 from the spindle 1 either to the rollers 27, 28, 29 of Figures 13, 14, or to the guide roller 9^a, Figure 5, the wire end projecting below the roller 29 or the guide roller 9^a has to be raised and has to be guided to 35 the wire eye of the shuttle, while reversing the direction of the wire. This reversal is assisted by providing the cam piece 31, Figure 13, by means of which the wire end is raised, so that it may be easily passed over the roller 29 or the guide roller 9^a, and conducted to the wire discharging means.

40 Instead of the guide rollers 11 of the form of construction according to Figures 5 and 6 a roller 36 is arranged in the construction according to Figures 16, 17 which is mounted in a bearing 41 of the shuttle wall 20 longitudinally displaceable by means of slots 37, 38 and pins 39, 40. The longitudinal displacement of the bearing 41 serves for compensating the change in the force required for the unwinding of the wire from the spindle 1, and according to its being effected from the left or from the right. The shuttle wall 20 is provided with an extension 43 for the mounting of the rollers 44, 45 over which the filling wire is passed upon leaving the shuttle. The dash-and-dot lines in Figures 13, 17 show the guiding of the wire. The shuttle wall 20, the adjustable bearing 41 and the extension

43 enclose a, for example, substantially pyramidal depression, socket or channel 46 in the top and bottom portions of which the head and foot portions of the roller 36 are mounted or countersunk, thereby accomplishing the result that jamming of the filling wire between the roller 36 and its bearing is prevented. By the provision of a plurality of rollers 27, 28 and 29 some of which are spring actuated a perfectly uniform playing off and pull of the wire with corresponding adjustment of the rollers is produced, even with hard wires, in which case the wire is simultaneously stretched, the device operating equally well with soft wire, such as brass wire or the like.

50 In order to avoid loosening of the guide rollers 11, Figures 5 and 6 of the drawing, their stud axles 15, after having been mounted in the insertion piece 10 of the shuttle wall 20 are provided with a slot 17, substantially of circular segmental shape and being continued through the shuttle wall 20 and passing through the head of the axial studs 15 to the extent of about half of their cross section, so that in the slot thus provided the likewise circular segmental locking plate 18 may be secured by means of screw 19. In the same manner the other axial studs, thus for instance the studs of the rollers 44, 45, Figure 19, may be locked in position.

55 The walls 20 of the shuttle may consist of thin material, such as steel sheets or the like, without impairing its strength, so as to further increase the capacity of the shuttle by the diminishing of the thickness of its walls.

60 Inasmuch as the spindle according to my invention is particularly designed for the handling of wire fillers, it is obvious that provision must be made to counteract both the heavy weight and great bulk of the material on the spindle, as well as the comparative lack of flexibility and the springiness and kinking of the wire, which latter, unless suitably provided for, would cause the wire to be snapped off and be caught and knotted by the warps and become jammed in the shuttle body. These drawbacks are overcome by the broadened shape of the spindle, as shown in Figures 11 and 12, in combination with the spring acting operating tensioning means and the pyramidal recess provided for their reception and the abutting face 31, causing the wire to be kept down and away from the walls of the shuttle, and by the special locking means 17, 18 provided for the tensioning rollers. Inasmuch as, moreover, the springiness of the wire causes a violent pull on the spindle in the axial direction, the spindle head is mounted upon and on both sides of the roller shaft, and is secured at both ends against undue longitudinal displacement by

the horizontally disposed pivotal connection and by the inclined or cam shaped abutting surfaces 1^r , 1^s which will counteract any slipping tendency of the pivotal connecting means. While these and other important features have been provided particularly in view of the utilization of my invention for the making of wire fabrics, it will be obvious that they will produce similar great advantages when applied to the insertion of fillers of other material, such as threads of fibrous material, cane and the like.

It should be understood that the invention is not limited to the particular construction, shape and arrangement of parts herein described and shown merely by way of exemplification of the principles thereof, and that the shape and arrangement of the shuttle body and of the spindle and their parts and accessories may be modified and varied from that herein shown, so as to better adapt the invention to existing conditions and the convenience of the operator, and without deviating from the spirit of my invention, as pointed out in the claims hereunto appended.

I claim:

1. The combination with a shuttle-body and a spindle mounted therein, of antifrictionally acting supporting means on the shuttle-body, a substantially longitudinally recessed head on said spindle, and pivoting means on the shuttle-body intermediate the supporting means and the adjacent end of the shuttle, and engageable with the recessed head.

2. The combination with a shuttle-body and antifrictionally operating supporting means thereon, of a spindle, a longitudinally recessed lateral end portion on said spindle above said antifriction supporting means, and pivoting means on the shuttle body intermediate the supporting means and the adjacent end of the shuttle, and engageable with the recessed spindle portion.

3. The combination with a shuttle body and a spindle therefor, of a longitudinally recessed lateral portion near one end of the spindle and rigidly secured thereto, pivoting means on the shuttle body, engageable with the recessed portion, and inter-engagable guiding and unyielding cam surfaces respectively disposed on the spindle and on the shuttle body intermediate their ends.

4. The combination with a shuttle body and antifrictionally operating supporting means thereon, of a spindle, a spindle head at one end thereof above said antifrictionally operating supporting means, a longitudinally recessed part on said head confronting the supporting means, pivoting means on the shuttle body intermediate the supporting means and the end of the shuttle and engageable with the recessed part of the head, and inter-engaging guiding cam sur-

faces respectively disposed at the rear end of the spindle head and on the shuttle-body.

5. The combination with a shuttle body, of a spindle, an axially extending spindle head thereon, a longitudinally recessed, endwise slotted lateral section on said head, pivoting means on the shuttle body detachably engageable with the slotted recessed section, inter-engaging guiding cam surfaces, respectively disposed at the inner end of the spindle head and on the shuttle body, and spring acting locking means on the shuttle body engageable with the spindle head.

6. The combination with a shuttle-body, of a spindle therefor, an axially extending spindle head thereon, revoluble antifrictionally acting supporting means on the shuttle underneath the spindle head and intermediate thereof, a longitudinally recessed and endwise slotted lateral section on said head, pivoting means on the shuttle body detachably engageable with the slotted recessed section at one end of the spindle head, and inter-engaging cam surfaces, respectively disposed at the other end of the spindle head and on the shuttle body, a shaft on which the supporting means are rotatably mounted, an endwise bevelled extension on said shaft, and transversely disposed spring acting locking means on the shuttle body engageable with the spindle head and with said bevelled extension.

7. The combination with a shuttle body, of a spindle longitudinally disposed therein, an axially extending, laterally recessed spindle head at one end of the spindle, pivoting means on the shuttle detachably engageable with the laterally recessed spindle head, thread-and-wire guiding means on the shuttle near the other end of the spindle, an abutment on the shuttle body spaced from the thread-and-wire guiding means intermediate the same and the adjacent end of the shuttle.

8. The combination with a shuttle body, of a spindle codirectionally disposed therein, an axially extending, laterally recessed spindle head at one end of the spindle, pivoting means on the shuttle detachably engageable with the laterally recessed spindle head, a laterally extended enclosing wall for the shuttle body, and a substantially pyramidal depressed hollow housing portion on said enclosing wall, thread-and-wire guiding means in said recessed portion, and thread-and-wire guiding means on the shuttle near the other end of the spindle, and an abutment on the shuttle body spaced from the thread-and-wire guiding means and adapted to cause the bending upon itself of the filling means fed from the spindle.

9. The combination with a shuttle body, of a spindle longitudinally disposed therein, an axially extending, laterally disposed spindle head at one end of the spindle, pivoting

means on the shuttle, detachably engageable with the laterally recessed spindle head, abutting means respectively disposed at the rear end of the spindle head and on the shuttle, thread-and-wire guiding and stretching means on the shuttle near the other end of the spindle, means to spring 5 actingly adjust part of said guiding and stretching means and bending means for the 10 filling material fed from the spindle, and opposite the guiding and stretching means.

10. In combination with a substantially flat shuttle body, a substantially flat, broad spindle housed therein, a longitudinally extending hook-shaped head on said spindle, and means on said shuttle, pivotally and detachably engaging with said hook-shaped head.

11. In combination with a substantially flat shuttle body, a laterally broadened spindle of substantially elliptical cross section codirectionally housed therein, a longitudinally extending hook-shaped head on said spindle, and means on said shuttle, pivotally and detachably engaging with said hook-shaped head.

12. In combination with a shuttle having greater width than height, a laterally broadened, substantially elliptical spindle with flat bottom, housed in the shuttle, a longitudinally extending, longitudinally recessed, endwise hook-shaped head portion on said spindle, and pivoting means on the shuttle 20 detachably engaging the hook shaped head portion.

13. The combination with a shuttle body and freely rotatable antifriction rollers near the ends thereof, of a spindle longitudinally disposed therein, and comprising a spindle head extending above and beyond one of said rollers, substantially hook-shaped pivoting means for the head and respectively disposed on the head and the shuttle body intermediate the roller and the end of the 40 shuttle, and thread-and-wire guiding and tensioning means on the shuttle body between the tail end of the spindle and the other roller.

14. The combination with a shuttle body and a spindle longitudinally disposed therein, of a spindle head near one end of the

shuttle and axially disposed, slotted pivoting means respectively disposed on the spindle head and on the shuttle body, thread-and-wire-guiding and tensioning means on the shuttle body beyond the tail end of the spindle, laterally disposed guiding and tensioning rollers on the shuttle body, and a substantially semi-circular locking plate on the shuttle body detachably engageable with the laterally disposed rollers.

15. In a loom shuttle for wire looms and the like the combination with a shuttle body and antifriction rollers in the terminal portions thereof, of a spindle of substantially laterally broadened cross section longitudinally disposed in said shuttle body, a spindle head above said rollers, inter-engaging pivoting means respectively mounted at the end of the spindle head and on the shuttle 70 body, abutting and sliding cam faces, respectively disposed at the other end of the spindle head and on the shuttle body, spring-adjusted wire guiding and tensioning means intermediate the tail end of the spindle and the adjacent shuttle end, and an abutment 75 near said guiding and tensioning means, adapted to bend the wire upon itself.

16. In a wire loom shuttle a substantially flat, laterally broadened spindle of substantially greater width than height throughout its length for the reception of the filling wire, and adapted to cause the springy broader arcuate portions of the wire to be retained by friction against the lateral narrower arcuate portions and against the sides of the spindle, and mounting means for the spindle.

17. In a wire loom shuttle a flat spindle of substantially throughout lenticular cross section and mounting means for said spindle at one end thereof.

18. In a wire loom shuttle a spindle of substantially throughout lenticular cross section, substantially hook-shaped mounting means axially and vertically disposed at one end of the spindle and integral therewith, and means on the shuttle engageable with the mounting means.

In testimony whereof I have affixed my signature.

JOHANNES RUDOLF PAUL IRMISCHER.
